HASP CONSTRUCTION

Application filed December 4, 1926. Serial No. 152,541.

The present invention relates to hasp construction.

The present invention will be described in connection with hasps such as are used upon railway box cars, though as the description proceeds it will be apparent that the invention is of broader application.

Car thieves display great ingenuity in breaking into box cars, and one vulnerable point of attack is the fastener for the hasp. A common form of hasp fastener comprises an elongated metal strap or bar secured to the car door on the outer side thereof. Another metal member is disposed upon said strap, secured to said strap or bar and to said door by rivets or the like. Said other metal member has a goose neck having its terminal seated in an aperture in said strap or bar. Said goose neck forms the hinge for the hasp. Car thieves have made a practice of prying said goose neck outwardly, whereby they may free said hasp from its hasp position and open the car door without disturbing the locking bolt or its sealing ribbon. After burglarizing the car, the thieves can close the car door, hammer the hasp back approximately into its proper relationship with the hasp or at least sufficiently close to said proper relationship to pass the car inspector without detection. Another expedient of car thieves is to clip the heads from the rivets which are used to hold in position the member having the goose neck above referred to. The thieves then remove said goose necked member in a simple movement, gain access to the car, and after having finished their thieving close the car door, reinsert the goose necked member referred to, and insert in the rivet holes members having heads simulating rivet heads, whereby the car will pass the car inspector without detection.

The present invention has for one of its objects the provision of a hasp construction which will effectually prevent the removal of the hasp when the car is in locked condition, even though the rivets holding the hasp fastener are removed.

A further object is to provide a hasp construction having a hasp fastener which

must be fastened in place at an angle to which said hasp fastener cannot be moved when the bolt cooperating with the hasp referred to is in locked position.

A further object is to provide a hasp fastener which is proof against any such prying operation as above referred to, but which is easy to assemble and disassemble when the car door is unlocked.

Further objects will appear as the description proceeds.

Referring to the drawings—

Figure 1 is a view in side elevation of part of a car side having one embodiment of the present invention applied thereto;

Figure 2 is a sectional view of part of a car side illustrating the present invention in top elevation, parts being broken away to illustrate the construction;

Figure 3 illustrates a detail of construction;

Figure 4 is a sectional view taken along the plane indicated by the arrows 4—4 of Figure 2; and

Figures 5 and 6 illustrate the details of a modified form of the present invention.

The numeral 10 indicates a sliding door, and the numeral 11 indicates the door frame cooperating therewith. The numeral 12 indicates a fitting comprising a holder for a reciprocating bolt 13, which bolt is provided with an elongated slot 14 adapted to receive the stud 15, which stud is rigid with the fitting 12. Any preferred collar or other abutment means, indicated by the numeral 16, may be employed for preventing outward movement of the bolt 13. Said fitting 12 is provided with the outwardly extending staple 17, said staple having the aperture 18 adapted to receive said bolt 13. The lower extremity of the bolt 13 is apertured, as indicated by the numeral 19, for cooperation with the sealing lug 20, whereby the usual sealing ribbon (not shown) may be used in sealing the bolt 13 in fixed relationship with the fitting 12.

Cooperating with the staple 17 and adapted to underlie the bolt 13 is the hasp 21, which is swingingly mounted upon the door 10 by a hasp fastener, indicated as a whole

by the numeral 22, which hasp fastener constitutes the subject matter of the present invention. Said hasp fastener 22 includes an elongated bar or strap 23, which may be riveted to the door 10 at a plurality of places along its length. Mounted upon the bar 23 is the goose necked member 24, having a pair of flanges 25—25. The goose necked member 24 also has the stud 26 extending rearwardly therefrom and fitting within a corresponding aperture 27 in the bar 23. Rivets 28—28 are provided for holding the bar 23 and goose necked member 24 in cooperative relationship with one another and with the door 10. In order to render it more difficult for a thief to chip off the heads of the rivets 28, the heads 29—29 may be set into counterbored portions 30—30 on the outer side of the goose necked member 24. The goose necked member 24 is provided with the goose neck 31, which has the enlargement 32 at its extremity. Figures 1 to 4, inclusive, show a preferred form of the extremity 32 of the goose neck 31. From an inspection of said figures, it will be noted that said head portion is square in configuration. The bar 23 is provided with a square aperture 33, said square aperture being only slightly larger than the square head portion 32 of the goose neck 31. The square head portion 32 and the square aperture 33 are so positioned relative to one another that said head portion may be inserted into said aperture only when the goose necked member 24 is disposed in an angular relationship with the bar 23 equal to approximately 45°. In order to provide space for the head portion 32 when the hasp fastener 22 is in position on the door, the material of the door 10 will, of course, be removed to a sufficient extent to permit the disposal of said head portion 32 within the outer bounding surface of said door 10.

A square configuration of the head portion 32 cooperating with the bar having a square aperture 33 is preferred for the reason that a square construction is simpler for the ordinary mechanic than is any other shape, except round. Moreover, the square construction provides four bearing surfaces for the head portion 32 against the under surface of the bar 23, making it an impossibility from a practical standpoint for a car thief to pry the goose neck 31 outwardly with reference to the bar 23.

Assembly and disassembly are relatively simple in the construction shown in Figures 1 to 4, Figure 1 showing in full lines the position of the goose necked member 24 relatively to the bar 23 when the square portion 32 is being inserted into or removed from the square hole 33.

Referring now to Figures 5 and 6, it will be noted that the round shank of the goose neck 31 has at its extremity an enlarged

shoulder 34, which as shown in Figure 6 comprises half of an annulus. The bar 23 is provided with an aperture for receiving the extremity of the goose neck 31, which aperture is similar in shape to the shape of the extremity of the goose neck 31, said aperture comprising a hole having two radii having a common center, said hole being slightly larger than the shank of the goose neck 31 and the shoulder 34 thereof. Though the hole in the bar 23 is similar in contour to the extremity in the goose neck 31, said extremity and said aperture are so arranged relative to one another that said extremity may be inserted into or withdrawn from said aperture only when the goose necked member 24 is disposed in angular relationship with the bar 23 equaling substantially 180°. With the hasp 21 in position upon the staple 17, it is a physical impossibility, even if the holding rivets 28 are removed, to move the goose necked member 24 into such 180° angular relationship with the bar 23, by reason of the fact that the hasp 21 constitutes an obstruction. It is a physical impossibility to move the goose necked member 24 into a position even approximating that which will permit the withdrawal of the shoulder 34 from the aperture in the bar 23. Assembly or disassembly of the goose necked member is readily accomplished, however, when the car door is unlocked and moved away from the door joint 11. Figure 5 shows in full lines the initial position of the goose necked member 24 in assembly, said member 24 on the bar 23, the broken line positions of the member 24 indicating an intermediate position and the final position of said member 24 relative to this bar 23 in assembling said member 24.

Though certain embodiments of the present invention have been described in detail, many modifications will occur to those skilled in the art. It is intended to cover all such modifications that fall within the scope of the appended claims.

What is claimed is—

1. In a fastener, in combination, two complementary members disposed one upon the other and secured together, one of said members having a substantially square aperture therein, the other of said members having a goose neck having its end portion extending through said aperture, said end portion having a shouldered portion underlying said one member, said shouldered portion conforming in outline to the outline of said substantially square aperture whereby to be insertable through said aperture in a right line movement when said members are disposed in substantially 45° relationship with one another, whereby when said members are juxtaposed said shouldered portion will underlie said one member substantially symmetrically.

2. Is a fastener, in combination, two com-

plementary members disposed one upon the other and secured together, one of said members having a substantially square aperture therein, the other of said members having a 5 goose-neck having its end portion extending through said aperture, said end portion having a shouldered portion underlying said one member, said shouldered portion conforming in outline to the outline of said substantially 10 square aperture, but being out of registry with said substantially square aperture when said complementary members are disposed in operative relationship with one another, the outlines of said shouldered portion and said 15 aperture being arranged symmetrically with each other.

3. In a fastener, in combination, two complementary members disposed one upon the other and secured together, one of said members having an aperture therein of polygonal contour, the other of said members having a goose neck having its end portion extending through said aperture, said end portion having a shouldered portion underlying said 20 one member, said shouldered portion conforming in outline to the outline of said aperture whereby to be insertable through said aperture in a right line movement when said members are disposed in substantially 25 45 degree relationship with one another, whereby when said members are juxtaposed said shouldered portion will underlie said one member substantially symmetrically.

4. In a fastener, in combination, two complementary members disposed one upon the other and secured to each other, one of said members having an aperture therein of polygonal contour, the other of said members having a goose neck having its end portion 30 extending through said aperture, said end portion having a shouldered portion underlying said one member, said shouldered portion conforming in outline to the outline of said aperture but being out of registry with 35 said aperture when said complementary members are disposed in operative relationship with one another, the outlines of said shouldered portion and said aperture being arranged symmetrically with each other.

5. Fastening means comprising, in combination, a bar fixed to a support and a member mounted flatwise on and secured to said bar, said member having a goose neck having its end portion disposed within an aperture in said bar, the extremity of said goose neck having a shoulder of rectangular contour, said shoulder projecting symmetrically from opposite sides of said goose neck and being insertable through said aperture in a 40 right line movement only when said member is out of parallel relationship with said bar, said shoulder, when said member is mounted in operative position upon said bar, underlying said member.

6. Fastening means comprising, in combi-

nation, a bar fixed to a support and a member mounted flatwise on and secured to said bar, said member having a goose neck having its end portion disposed within an aperture in said bar, the extremity of said goose neck having shouldered portions extending symmetrically from opposite sides of said goose neck, the shouldered portions of said goose neck being of a shape similar to the shape of said aperture but being disposed out of registry with said aperture when said member is in its normal position upon said bar, said goose neck being insertable through said aperture in a right line movement when said member is moved in the plane of said goose neck but is disposed out of parallel relationship with said bar.

7. Fastening means comprising, in combination, a bar fixed to a support, a member mounted flatwise upon and secured to said bar, said member having a goose neck having an end portion disposed within an aperture in said bar, said end portion having its extremity shouldered symmetrically on the two sides of said goose neck, said shouldered portion being disposed in abutting relationship with the under side of said bar, the configuration of said shouldered extremity and said aperture being so related that said goose neck is withdrawable from said aperture when said member is moved in the plane of said goose neck provided said member is shifted about the axis of said aperture from its normal position upon said bar.

Signed at Chicago, Illinois, this 1st day 70 of December, 1926.

KENNETH J. TOBIN.
